ABSTRACT: A selected group of edge-notched cards, to be removed from other cards of a stack, are moved downwardly onto selector bars relative to the other cards, preferably with the assistance of a physically engaging device such as a brush. The other cards are then moved rearwardly, after which the selected cards are raised and moved forwardly for removal. The card-supporting and moving members may be operated by means connected to a common camshaft for proper sequential operation. A card punch mechanism may be operable with the selector bars for notching the cards.

CARD-SORTING METHOD AND APPARATUS

BACKGROUND

This invention relates to card sorting; and in particular, it relates to the sorting of edge-notched cards.

Numerous arrangements are presently known for sorting edge-notched cards. These range from simple mechanical elongated rod devices to complex automatic machines. However, all known methods and apparatus are limited in one way or another. The manual devices are either too slow or they are of insufficient capacity, while the complex automatic machines tend to be quite expensive. Further, the complexity of these automatic machines greatly increases the probability of a malfunction.

Thus, there exists a need for a new and improved card sorting method and apparatus which will strike a more advantageous balance between simplicity, capacity, economy and reliability.

SUMMARY OF THE INVENTION

Thus, it is a purpose of this invention to provide a new and improved card-sorting method and apparatus which overcomes many of the problems and disadvantages of previously known card-sorting arrangements. This purpose of the invention is accomplished by providing a new procedure for manipulating the cards in an efficient manner; and also a new and improved apparatus for carrying out this procedure feature, the said apparatus being constituted by a unique arrangement of interrelated operating elements, which arrangement is compact in size as well as economical to produce and reliable in operation.

In accordance with the method of the present invention, a stack of cards containing a random collection of both selected cards and cards to be rejected is arranged with an edge of all cards of the stack in alignment with each other, the notches being formed on said aligned edges. A predetermined combination of selector bars are presented to the aligned edges, the said combination corresponding to the pattern of the notches in the cards to be selected and removed from the stack. The selected cards are moved towards the selector bars in a first direction, after which the rejected cards are moved in a second direction generally perpendicular to the said first direction. The selected cards are then moved in a third direction, generally opposite to the said first direction, after which the selected cards are engaged and moved in a fourth direction, generally opposite to the said second direction. The selected cards then project in the said fourth direction and are relative to the rejected cards thus positioned for removal from the remaining (i.e. rejected) cards of the stack.

The present invention also includes an apparatus for carrying out the method of the present invention, said apparatus comprising a bank of selector bars flanked by front and rear vertically movable riser bars. The aligned edges of the cards are arranged to extend from the front riser bar, across the bank of selector bars to the rear riser bar. In operation, the cards are first supported on and above the front and rear riser bars. In one embodiment the tops of the selector bars are at a slightly lower level than the tops of the riser bars. However, to facilitate insertion of the cards, the machine may also be constructed with the tops of the selector bars even with the tops of the riser bars. Certain selector bars corresponding to the predetermined notch pattern are then raised relative to the other selector bars, after which the front and rear riser bars are moved downwardly, permitting the stack of cards to fall onto the selector bars, and further permitting the selected cards having the predetermined notch pattern to move downwardly relative to the other cards since all the raised selector bars enter notches in the selected cards. The rejected cards not having the predetermined notch pattern then rest on top of the raised selector bars since at least one raised selector bar will not be aligned with a notch on each and every rejected card. The rejected cards, which are now in a raised position

relative to the selected cards, are moved rearwardly at least until the front edges of the rejected cards are to the rear of the front riser bar. The front riser bar is then moved upwardly, raising only the selected cards, until the front ends of the selected cards are located above the upper corner of the tops of the rejected cards. Suitable means then engage the raised selected cards and move them forwardly to a position whereat they can be conveniently removed from the remaining (i.e. rejected) cards of the stack.

10 In accordance with a feature of the present invention, the front and rear riser bars, the set of selector bars and the means for moving the cards rearwardly and forwardly are all operatively connected to a common control means whereby proper sequential operation of these elements is assured. More specifically, this arrangement may include a motor-operated shaft having a plurality of cams mounted thereon, one of said cams being operatively connected to said front riser bar, another cam being operatively connected to said rear riser bar, another cam being operatively connected to the set of selector bars, and another cam being operatively connected to the means for moving the cards forwardly and rearwardly.

15 In accordance with another feature of this invention, the means for moving the rejected cards rearwardly and then moving the selected cards forwardly may comprise the cover member of the apparatus, the cover member being mounted for forward and rearward movement to effect said forward and rearward movement of the cards, and also for upward movement to facilitate insertion of the stack of cards into the apparatus and removal of the rejected cards after the sorting procedure. However, notwithstanding these separate functions, the cover member is still of sufficient size and is positioned to act as a dust cover to keep dust off of the cards.

20 Another feature of the invention comprises a new and improved arrangement for causing the selected cards to move downwardly in the first direction relative to the remaining cards of the stack. Contrary to previous arrangements which have relied upon forced air, vibration and the like, with this feature of the present invention, means are provided for physically engaging the cards and ruffling the same, thereby providing a means for positively engaging and moving the selected cards. In a preferred arrangement of the present invention, this means comprises rotating brushes which engage the top and side of the stack of cards. The bristles of the brushes are 25 so constructed that they will apply a sufficient force to the selected cards to move the same downwardly onto selector bars, thereby overcoming frictional and electrostatic forces tending to hold the selected cards in the stack. Concurrently, the bristles should contain sufficient resilience such that when they engage the rejected cards which cannot be moved, they will yield rather than damage the rejected cards.

25 In accordance with another feature of the invention, the apparatus includes an arrangement for punching notches of any desired pattern in an edge of a card, the punching apparatus being operable in combination with the selector bars of the apparatus. More specifically, the arrangement may include a means mounted on the side of the apparatus adjacent one end of the selector bars, for holding a card to be punched. In one 30 embodiment the edge to be punched is placed in a recess containing a plurality of notching devices, one notching device being provided for each possible notch position on the edge of the card. Each notching device is mounted, relative to the selector bar corresponding to that position, such that the notching device is operative to punch the card when that selector bar is selected (that is, moved sideways from its normal position) and then raised. Therefore, in operation, the operator would place the card to be punched into the means for holding the card and then operate the sorting apparatus in 35 exactly the same manner as he would at the start of a sorting procedure, namely by punching a keyboard or the like to select certain selector bars corresponding to a predetermined notch pattern. By then raising the chosen selector bars, the operator would automatically actuate the notching devices to 40 notch the card. In another embodiment, a single notching

device travels along the card edge to be notched, stopping to perform a notching operation whenever it engages a selected selector bar, that is, a bar which has been moved sideways from its normal nonactuated position.

Thus, it is an object of this invention to provide a new and improved card-sorting method and apparatus.

It is another object of this invention to provide a new and improved method and apparatus for sorting edge-notched cards wherein the cards are manipulated to move the selected cards downwardly, the rejected cards rearwardly, the selected cards upwardly, and then the selected cards forwardly for removal.

It is another object of this invention to provide a new and improved arrangement wherein the various means for manipulating the cards are operatively connected to a common control means for assuring predetermined sequential operation of these parts.

It is another object of this invention to provide a new and improved arrangement for causing initial separation of selected edge-notched cards from the remaining cards of the stack, including means for physically engaging the cards of the stack.

It is another object of this invention to provide an arrangement including a rotating brush for causing initial separation of selected edge-notched cards from a stack of edge-notched cards.

It is another object of this invention to provide a card-sorting apparatus wherein the cover member of the apparatus is movable and serves the additional function of engaging and moving the cards during various stages in the card-sorting procedure.

Another object of this invention is to provide, in combination with a card-sorting apparatus, a means for punching notches in the edge of cards.

Other objects and the attendant advantages of the present invention will become apparent from the detailed description to follow and also the accompanying drawings.

BRIEF DESCRIPTION OF THE DRAWINGS

There follows a detailed description of a preferred embodiment of the present invention, together with accompanying drawings. However, it is to be understood that the detailed description and the accompanying drawings are provided solely for the purpose of illustrating a preferred embodiment, and that the invention is capable of numerous modifications and variations apparent to those skilled in the art without departing from the spirit and scope of the invention.

FIG. 1 is an external, partially schematic, perspective view of an apparatus constructed in accordance with the features of the present invention.

FIG. 2 is a vertical cross-sectional view taken in a vertical plane through the line 2-2 of FIG. 1.

FIG. 3 is a vertical sectional view taken through a vertical plane through line 3-3 of FIG. 1.

FIG. 4 is a vertical sectional view of a portion of the apparatus taken along line 4-4 of FIG. 2.

FIG. 5 is a vertical sectional view of a portion of the apparatus taken along line 5-5 of FIG. 2.

FIG. 6 is a vertical sectional view of a portion of the apparatus taken along line 6-6 of FIG. 2.

FIG. 7 is a side elevational view of the apparatus and is taken along a vertical plane passing through line 7-7 of FIG. 2.

FIG. 8 is a partial elevational view of the apparatus taken along line 8-8 of FIG. 2.

FIG. 9 is a partial elevational view of the apparatus taken along line 9-9 of FIG. 2.

FIG. 10 is a partial sectional view taken on line 10-10 of FIG. 9.

FIG. 11 is a partial development view of the brush, a part of which is shown in FIGS. 9 and 10.

FIG. 12 is a plan view of the portion of FIG. 3 showing the card-punching device.

FIG. 13 is a vertical sectional view showing a portion of the apparatus and taken along line 13-13 of FIG. 3.

FIG. 14 is a plan view of another embodiment of the card-punching device.

FIG. 15 is a side elevational view taken in the direction of the arrow P in FIG. 14.

FIG. 16 is an end elevational view taken in the direction of the arrow Q in FIG. 15.

FIGS. 17A through 17F illustrate the manipulation of the cards for carrying out the sorting procedure.

DETAILED DESCRIPTION OF THE PREFERRED EMBODIMENT

15 Referring now to the drawings, like numerals are used to represent like elements throughout the specification.

FIG. 1 is a generally schematic view of a card-sorting apparatus 20 constructed in accordance with the features of the present invention. The apparatus includes a front opening 21 to an interior space bounded by sidewalls 22 and 23 and a rear wall 24. A cover member 25 is located above the interior space. This cover member is capable of moving forwardly and rearwardly as indicated by the arrow A and it is also capable of swinging upwardly as indicated by the arrow B. A card-engaging lip 26 extends transversely across the front of the cover member 25. The bottom of the interior space of the apparatus includes a fixed front partition 30, front and rear riser bars 27 and 28, and a set of selector bars, indicated generally as 29. In a preferred embodiment, the set consists of 55 selector bars.

20 Although the operation of the invention will be explained in greater detail below, it would be helpful at this point to understand the basic operation of the elements described above and illustrated in FIG. 1. The cover member 25 is pivoted upwardly about an axis located toward the rear of the apparatus 25 and the stack of cards to be sorted is placed in the interior space such that the front and rear of the stack rest on riser bars 27 and 28, respectively. The cover member 25 is then lowered to the position shown in FIG. 1. The cards are then 30 acted upon by movement of the cover member 25, the riser bars 27 and 28, the set of selector bars 29, and also a brush separator device. At the end of this manipulation the selected cards, that is the cards having a predetermined notch pattern along their lower edges, project outwardly through the opening 21, preferably beyond the front partition 30, whereat the selected cards can be conveniently removed.

35 It is a feature of the invention that the various elements are operated in proper sequence. This is accomplished by means of camshaft 40 which is driven by means of a motor 41 through suitable gearing 42 and 43, the latter being connected to the shaft by means of key 44. Fixed on this shaft are a plurality of cams which rotate with the shaft and which control the movement of the cover member 25, the riser bars 27 and 28, and the set of selector bars 29. The shaft 40 is supported in 40 roller bearings 48R and 48L which are mounted in sidewalls 22 and 23, respectively.

45 A set of cams 45L and 45R control movement of the selector bars 29. The cams 46L and 46R control movement of the rear riser bar 28 and the cams 47L and 47R control movement of the front riser bar 27.

50 FIG. 3 illustrates the means for operating the selector bars, and in particular, a specific selector bar 29A. As noted above, a preferred embodiment of the invention includes 55 selector bars, all of which are substantially identical to the selector bar 29A shown in FIG. 3. The selector bars are supported by the sidewalls 22 and 23, and also by additional guide plates 22A and 22B which are adjacent the sidewall 22, and guide plate 23A and 23B which are adjacent the sidewall 23 (see also FIG.

55 7). The selector bars are capable of undergoing sliding movement from right to left and left to right as shown in FIG. 3. It will be noted that the selector bars include lower recesses 60 which, in the normal position of the bar, are positioned immediately above right and left lift bars 64. Adjacent the 75 sidewall 22 there is provided a bank of solenoid devices 61,

one for each of the 55 selector bars 29. The solenoids are mounted on suitable frames 63. The solenoid device 61A which operates the selector bar 29A, includes an armature 62 which engages the end of selector bar 29A. If it is desired to select the specific selector bar 29A, the solenoid 61A is actuated, as a result of which the armature 62 engages the end of selector bar 29A and urges it to the right, (as shown in FIG. 3) until the end 60' of the recess adjacent sidewall 22 engages the side of its respective lift bar 64. After all of the desired selector bars have been moved to the right (as shown in FIG. 3) the lift bars 64 are raised. It can be seen that the lift bars 64 will engage and move upwardly only those selector bars which have been moved by their respective solenoid devices. The lift bars 64 will enter the recesses 60 of the remaining selector bars.

Adjacent the sidewall 23, the apparatus includes a special mechanism 70 for punching a predetermined pattern of notches in a card. This mechanism will be explained in greater detail below.

Referring now to FIG. 4, a selector bar lever 75, which is mounted for pivoting movement about a fixed pivot axis 76, includes at one end thereof a cam-following roller 77 which engages the surface of cam 45L. At its other end, the lever 75 is connected by means of a screw 78 to one of the two lift bars 64. This lift bar includes a pair of elongated slots 79 which permit vertical movement of the lift bar 64 relative to fixed guide pins 80. Thus, when the roller 77 engages the raised portion of cam 45L the lever 75 will pivot about axis 76 such that the lift bar 64 is moved upwardly, raising those selector bars which have been moved laterally by their respective solenoid devices of the bank 6.

FIG. 5 illustrates the operation of the rear riser bar 28. A rear riser bar lever 85 is mounted for pivoting movement about a fixed pivot axis 86. Attached at one end of the lever 75 is a cam-following roller 87. The other end of lever 85 is attached to the riser bar 28 by means of screw 88. Thus, as the roller 87 engages a high portion of cam 46L, the riser bar 28 will move upwardly.

FIG. 6 illustrates the elements for operating the front riser bar 27. A front riser bar lever 90 is mounted for pivoting movement about fixed pivot axis 91, and includes a cam-following roller 92 at one end and a screw 93 at its other end for connecting the said other end to the front riser bar 27. The lever 90 also includes a recess 94 to accommodate the rear riser bar 28 so that upward movement of the rear portion of lever 90 (which, in effect, is downward movement of front riser bar 27) does not affect the rear riser bar 28.

FIGS. 2, 7 and 8, illustrate the elements for causing movement of the cover member 25. Referring first to FIG. 2 and 7, an eccentric cam 49 is mounted on at least one end of shaft 40. This cam 49 is located within an enlarged recess 53 in a drive arm 50. This drive arm 50 is mounted for pivoting movement about a fixed pivot axis 52. A pin 51 extends through and inwardly from the drive arm 50. Referring now to FIG. 7, this pin 51 is located between front and rear stop screws 101 and 102 of the left sideplate 104 of the cover member 25. When the drive arm 50 is moved counterclockwise about its pivot 52, the pin 51 engages the stop screw 101 to drive the cover member 25 forwardly. And conversely, clockwise movement of the drive arm 50 will cause pin 51 to engage the stop screw 102 to move the cover member rearwardly. Concurrently, however, the cover member is free to be lifted by being turned clockwise about pivot pin 51 (as viewed in FIGS. 7 and 8). Thus, it can be seen that turning movement of the cam shaft 40 causes forward and rearward movement of the cover member 25. However, it is also necessary to effect vertical movement of the cover member 25 during its forward and rearward movement. The means for accomplishing this vertical movement are shown in detail in FIG. 8. FIG. 8 illustrates the front portion of sideplate 104. At the forward end of sideplate 104, there is provided a mounting 105 for holding the transversely extending lip 26. A cam plate 106, attached to the plate 104, includes a horizontal upper surface and a

downwardly extending tip 107. The plate 104 also has formed therein a recess 108.

Attached to the corresponding sidewall 23, is a cam 110 having an upwardly projecting end. As the cover member 25 moves rearwardly the tip 107 of the plate 106 rides along the surface of cam 110 as a fixed pin 109 engages the upper surface of plate 106 to hold the cover member 25 down. At this time the upwardly projecting portion of 110 is located in the recess 108 so that it does not cause upward movement of the cover member 25. A point is then reached at which the cam plate 106 passes behind the fixed pin 109, and tip 107 engages and rides up the upwardly projecting part of cam 110. At this time, of course, the cover member 25 is raised slightly upwardly as indicated by moved position in FIG. 8. In the operation of the device it is desired that during return movement of the cover member 25 towards its forward position, the cover member be held in this slightly raised position until the cover member is almost at its forwardmost position. This is accomplished by elements 111 through 114. In the absence of these elements, as the cover member 25 moved forwardly, the tip 107 would ride over the upwardly projecting part of cam 110 after which the cam member 25 would be lowered. The elements 111 through 114 comprise a screw 111, connected at one end to the cam 110 and connected at its other end to a guide pin 112, the latter being slidable in slot 113. Cam 110 is urged to the right (as shown in FIG. 8) by the spring 114. Thus, in operation, as the cover member 25 is moving forwardly, and the tip 107 engages the upwardly projecting part of cam 110, rather than ride over this part, it will cause this part to be moved forwardly (to the left in FIG. 8) until the head on guide pin 112 reaches the forward end of slot 113, after which the tip 107 will ride over the said upper portion of cam 110 so that the cover member 25 will be lowered in its forwardmost position.

At a certain stage during the operation of the invention, the selected ones of the selector bars are raised, and the stack of cards is released such that the selected cards will move downwardly relative to the remaining cards of the stack as the latter are held in the upper position by engagement of their lower edges on top of the raised selector bars. However, because of frictional and electrostatic forces between the selected cards and the remaining cards of the stack, the selected cards will not move freely. Thus, it is necessary to exert a force of some kind on the stack of cards to cause the selected cards to move. In the past, vibration, forced air, magnetic attraction and the like have been employed for this purpose. However, a feature of the present invention includes a new and improved arrangement for effecting separation of the selected cards from the remaining cards at this point. Specifically, the arrangement includes a means, preferably one or more rotating brushes, which physically engage the stack of cards for ruffling the cards of the stack to overcome the forces preventing the downward movement of the selected cards.

Referring now to FIGS. 9 and 10, there is shown, adjacent the right sideplate 120 of the cover member 25, a brush motor 121 which rotates a drive wheel 122 which in turn drives a belt 123. This belt 123 in turn operates an idler pulley 124 rotating this pulley 124, about fixed axis 125. This idler pulley 124 in turn operates belts 126 and 128 for turning brushes 127 and 129, respectively. As shown in FIG. 11, in a preferred embodiment, the brushes include a staggered arrangement of bristles. The brush is divided into a plurality of "bays," each bay having a plurality of axially extending brushes staggered axially and spaced apart around the periphery of the brush. This has the advantage of reducing power requirements since only a portion of the stack of cards is acted on at any given moment. In one preferred embodiment of the invention, there are ten "bays," each having a total thickness w of 1.2 inches which is equal to the width of 100 cards, the total device thus being 12 inches long and holding 1,000 cards. Each bay includes six brushes with a length X equal to 0.4 inches and spaced equally, i.e. at 60° intervals, about the periphery of the brush. The brushes overlap axially by an amount Y equal to 0.05

inches such that each bristle presents a nonoverlapping portion of a length Z equal to 0.3 inches. The apparatus can include a divider plate physically separating each bay from its adjacent bays.

Also visible in FIG. 9 is a portion of a rear abutment member 130 attached to the cover member 25 and extending across the rear of the apparatus above the front of brush 129 for locating the rear end of the cards as they are initially placed into the apparatus.

The present invention also includes a new and improved means for punching a desired pattern of notches in the cards, one embodiment of which is shown in FIGS. 3, 12, and 13. Referring to FIG. 3, there is shown a punch 140 and a die 141. These elements abut on the left-hand side (as shown in FIG. 3) but they form a recess 142 at their other side. The purpose of this recess is to receive the edge of the card to be punched. Each punch and die elements are urged downwardly by a spring 145, which acts against an upper abutment 146, urging the punch and die against a lower abutment 147. It will be noted that the lower portion of punch 140 is adjacent the end of selector bar 29A. Thus, if the selector bar 29A were in its actuated position (to the right from its position as shown in FIG. 3) and if the selector bar were then moved upwardly, this would move the elements 140 and 141 upwardly against the force of spring 145. Referring to FIGS. 12 and 13, it will be seen that there are a plurality of punch and die units 140 and 141, one such unit for each possible punch position along the edge of a card. The unit includes a holding device 148 for holding a card 144 to be punched so that its appropriate edge fits into the recesses 142 of all 55 punch and die units. FIG. 13 illustrates one punch and die unit in its actuating position, actuated by its respective selector bar 29. It will be noted that the upper edge of punch 140 adjacent the recess is curved. This is to assure proper movement of a punch 140 between adjacent dies 141 as it moves upwardly. The remaining edges of the punch 140 are of course straight and they act by shearing the edge against the lower edges of the said adjacent dies 141 to remove the material from the card 144 and hence form the notch.

As noted earlier, movement of the selector bars 29 to the right (from the position as shown in FIG. 3) places them in such a position that upward movement of these bars will activate the appropriate punch and die units. However, when forming punches in a card, it will not necessarily be desired to concurrently start the motor 41 to operate the apparatus. Therefore, the necessary upward movement of the selector bars 29 for operating the punch and die units may be brought about by means of a solenoid 160 which operates through a suitable lever system 161 so that surface 162 thereof abuts the lower right-hand edges of the appropriate selector bars causing upward movement thereof.

It is also necessary to form notch in the edge of the cards opposite from that edge containing the predetermined pattern of notches for engagement by the transversely extending lip 26 for moving the cards. Referring to FIGS. 3 and 12, the apparatus includes, for this purpose, a die 150 and a punch 151, the latter being actuated by means of a solenoid 152. The apparatus is mounted on the holder 148 by means of a suitable frame 153.

FIGS. 14 through 16 illustrate an alternative embodiment of a means for punching a desired pattern of notches in the cards.

In this apparatus 200, the card 201 to be punched is slid into the card guide plate 202. A punch assembly 203 includes a guide member 203A which is located in a recess 204, in the sidewall 23 and movable longitudinally in said recess, (from right to left and left to right as shown in FIGS. 14 and 15). A motor 205, mounted on the apparatus turns a drive pulley 209 which in turn moves a cable 206 about idler pulleys 207. The cable 206, as shown, is wound three times about 209. The cable 206 and the pulley 209 are constructed such that, while the cable is normally driven by the pulley 209, it can slip relative thereto, when another means prevents movement of cable 206. For this result the cable 206 may be, for example, a

nylon-covered stainless steel braided cable and the pulley 209 may be a polished steel drum. The ends of cable 206 are held by clamp 208. End 206a is knotted while end 206b is held firmly by clip 208a of clamp 208. Clip 208a can be loosened and the end 206b moved, as desired, for adjusting the tension in the cable 206.

To start the punching cycle, the appropriate selector bars 29 are first moved by their respective solenoids of the bank of solenoids 61 in exactly the same manner as with the previously 10 described embodiment of the punching device. Such a moved selector bar is shown in the FIGS. at 29. See in particular FIG. 16.

To start the operation of the device 200, the card is placed into the guide plate 202 while the assembly 203 is located at the far left (as viewed in FIGS. 14 and 15). The motor 205 is then operated to turn the cable to move the assembly 203 from left to right. The assembly 203 will continue its movement to the right until its plunger 210 engages the projecting selector bar 29. This will cause electrical contacts 211 to close thereby actuating a solenoid device 212. This in turn forces a plunger arm 213 downwardly thereby turning a punch-actuating lever 214 downwardly about its pivot axis 214A, and this lever 214 in turn acts directly upon a punch 215 of the assembly 203 urging the same downwardly through the edge of the card, thereby effecting the notch, and into a mating recess in a die 216, the latter also forming a part of the assembly 203. It will be noted that the elongated lever 214 will act on the punch 215 regardless of the position of the punch 215 along the length of the device.

When the punch reaches its full downward travel, a limit switch (not shown) is tripped, thereby deenergizing the solenoid 212. At this time, return spring 217 moves the punch 215 to its original position. This in turn trips another limit switch (not shown) which actuates a solenoid 218. As best shown in FIG. 16, solenoid 218 turns a lever 220 clockwise about its pivot axis 221 thereby causing an elongated bar 222 to move to the right (as shown in FIG. 16). This in turn acts upon a plunger 219, which is mounted in and travels with the assembly 203, to the right (as shown in FIG. 16) thereby urging the selector bar 29 to its retracted, original position.

During the entire punching procedure, the pulley 209 was turning. However, the cable 206 was slipping, relative to the pulley 209, because of the nature of the engagement between these elements. Thus, after the selector bar 29 is moved to its original position the assembly 203 is now free to and in fact does travel with the cable 206 until the plunger 210 engages the next displaced selector bar. At this time, the punching procedure, as recited above, is repeated. When the assembly 203 has completed its movement from left to right (as shown in FIGS. 14 and 15) a limit switch, not shown, is tripped, thereby reversing the rotation of motor 205 causing the punch assembly 203 to return to its original position at the left (as shown in FIGS. 14 and 15) end of the device. When the assembly reaches this left end position, it trips still another limit switch (not shown) thereby completing the cycle and cutting off the motor 205.

This arrangement also includes a device 223 for forming a notch in the top of the cards, this device being identical to the unit 150 in the previously described embodiment of the punching device.

The method of the invention and the operation of the apparatus will now be explained in detail with special reference to diagrammatic FIGS. 17A through 17F in which the proportions of some elements have been exaggerated to facilitate explaining the operation of the invention. In these figures, the letters S and R represent the selected and rejected cards, respectively. Further, the arrows shown in these figures represent movement which will take place as the various elements move between the position in which the arrows are shown and the next position.

Referring to FIG. 17A, the stack of cards including both the to be selected and the to be rejected cards, are placed into the interior of the apparatus 20 behind front partition 30 so that

they rest on front and rear riser bars 27 and 28. At this time all selector bars 29 are in their lowered position. At this time the code of the card or cards to be retrieved is entered on a keyboard (not shown) which in turn operates the desired combination of solenoids of the bank of solenoids 61. This moves the chosen selector bars laterally, in position to be raised. At this time the cams 45L, 46L and 47L are in the positions as shown in FIGS. 4 through 6. Of course, the corresponding cam, 45R, 46R and 47R, respectively, are symmetrical and are thus in the same positions as shown in FIGS. 4 through 6. Also, the eccentric 49 is in its forwardmost position which corresponds to the forwardmost position of the cover member 25.

The motor is now operated to turn the camshaft 40. This turns the cams 45 through 47 in the direction as indicated by the arrows in FIGS. 4 through 6. First, the lift bars 64 are raised to raise the selected ones of the selector bars 29. Almost immediately thereafter, the low points of the cams 46 and 47 act through their appropriate levers to cause downward movement of the riser bars 27 and 28. This position is shown in FIG. 17B. In the absence of frictional and electrostatic forces, the selected cards would move downwardly at this time as the notches of the selected cards moved onto the raised selector bars, while the bottoms of the rejected cards would rest on top of the raised selector bars. However, since frictional and electrostatic forces must be considered, an additional means is required at this time to act on the stack of cards to cause the selected cards to move downwardly. At this time the motor 41 may be stopped while motor 121 is operated to rotate the separator brushes 127 and 129. As a result of this movement, the selected cards move downwardly and the cards assume the positions shown in FIG. 17C.

At this time the time delay times out, once again energizing the cam motor 41 to turn the camshaft 40. At this time the extended lower surfaces L of the cams 46 and 47 engage their respective rollers to hold the riser bars down and the selector bars up while concurrently the eccentric 49 acts to move the cover member rearwardly so that the transverse lip 26 moves rearwardly from its original forward position as shown in FIG. 17A (see also FIG. 7) until it engages the notches in the upper edges of the rejected cards to move the same rearwardly from the position of 17C to the position 17D. At this time the raised surfaces H of the cam 46 and 47 reach their respective rollers to raise the riser bars 27 and 28. However, it is evident that the first part of the raised portion of cam 47 is higher than that of cam 46. The purpose of this is to raise the front riser bar 27 higher than the rear riser bar 28, thereby tilting the front of the selected cards upwardly, above the upper level of the rejected cards, to the position as shown in FIG. 17E. At this time, the cover member again commences its forward movement, the vertical position of the cover member being such that its transversely extending lip 26 engages the upper notches of the selected cards and moves the same forwardly such that when the lip 26 has reached its original forward position, the fronts of the selected cards (forward of the notch) extend beyond the front partition 30 so that the selected cards can be conveniently removed from the apparatus. Meanwhile, during this forward movement of the cover member, and of the selected cards, abutment member 130 engages the rear of the rejected cards to move the same forwardly to the original position over the riser bars 27 and 28. At this time the selected cards are removed and the selector bars dropped. The rejected cards can then be removed, or alternatively, they are in position for a subsequent sorting cycle. When the cover member reaches its left-hand position, it activates a limit switch (not shown) to turn off the apparatus.

Although the invention has been described in considerable detail with respect to a preferred embodiment thereof, it will be apparent that the invention is capable of numerous modifications and variations apparent to those skilled in the art without departing from the spirit and scope of the invention.

We claim:

1. Apparatus for mechanically sorting certain selected cards from a stack of cards containing a random collection of both

selected cards and cards to be rejected, comprising, a means for positioning said stack of cards such that at least one edge of all cards of the stack are in alignment with other means for moving the selected cards in a first direction relative to the rejected cards to separate the said edges of the selected cards from the said edges of the rejected cards in the said first direction, means for moving the rejected cards in a second direction generally perpendicular to the first direction, relative to the selected cards, and means for moving the selected cards in a third direction generally opposite to the said first direction.

5 2. The apparatus of claim 1 including means operable after the last said means for moving the selected cards in a fourth direction generally opposite to the said second direction.

15 3. The apparatus of claim 1 wherein the cards are edge notched cards and wherein cards having a predetermined notch pattern are separated from other cards of a stack which do not have the predetermined notch pattern, and wherein said aligned edges of the cards containing the notches and are the lower edges of the cards.

20 4. The apparatus of claim 3 including a set of selector bars positioned below the cards, and means for raising certain ones of said selector bars corresponding to said predetermined pattern of edge notches.

25 5. The apparatus of claim 4 including front and rear vertically movable riser bars mounted below the cards for supporting the same.

30 6. The apparatus of claim 5, said front and rear risers are initially located at a level at least as high as the certain selector bars for supporting the stack of cards, and including means for subsequently lowering the front and rear riser bars below the tops of the selector bars to permit the cards to move onto the selector bars, whereby the selected cards move in said first direction lower than the rejected cards as the nonnotched parts of the selected cards move below the top of the raised certain selector bars.

35 7. The apparatus of claim 6, wherein said means for moving the rejected cards in the second direction includes means for engaging the upper portions of said rejected cards.

40 8. The apparatus of claim 7 wherein said apparatus includes a cover member located above the cards and movable in said second direction, and wherein said cover member includes an element which engages the rejected cards and moves the same in said second direction.

45 9. The apparatus of claim 8 including a rotatable camshaft, said camshaft having at least four cams fixed thereon, the first cam operatively connected to said selector bars for raising the certain selector bars, the second and third cams operatively connected to said front and rear riser bars, respectively, and the fourth cam operatively connected to the cover member, whereby, by rotating said camshaft, said selector bars, said riser bars, and said cover member are operated in predetermined sequence with each other.

50 10. The apparatus of claim 8, wherein said cover member also constitutes a means for moving the selected cards in a fourth direction, opposite to said second direction, after the selected cards have been moved in said third direction until at least a part of said selected cards are located above the rejected cards.

55 11. The apparatus of claim 7 wherein the said means for moving the selected cards in the third direction comprises said front riser bar which is movable upwardly, independently of the rear riser bar, after the rejected cards have been moved in the second direction.

60 12. The apparatus of claim 11 including a camshaft having at least three cams fixed thereon, a first cam operatively connected to said selector bars to raise the same, a second and a third cam operatively connected to said front and rear riser bars, respectively, whereby, by rotating said camshaft, said selector bars, and said front and rear riser bars are operated in predetermined sequence with each other.

65 13. The apparatus of claim 6 wherein said means for moving the selected cards in the first direction, after the downward

movement of the riser bars, comprises a means for physically engaging the cards.

14. The apparatus of claim 13 wherein said last said means comprises a rotating brush.

15. The apparatus of claim 13, wherein the last said means comprises at least two rotating brushes for ruffling the cards to cause the selected cards to drop relative to the rejected cards, one of said brushes engaging the top of the stack, and the other brush engaging a side of the stack.

16. The apparatus of claim 15 wherein said brushes include at least one set of axially extending, axially and circumferentially staggered bristles for exerting a force on the cards as the brushes rotate.

17. A method of sorting selected cards from a stack of cards containing a random collection of both selected cards and cards to be rejected, comprising the steps of, arranging the stack of cards with an edge of all cards of the stack in alignment with each other, moving the selected cards in a first direction such that the said edge of the selected cards are positioned outwardly beyond the said edges of the rejected cards, moving only the rejected cards in a second direction which is generally perpendicular to the first direction, and then moving the selected cards in a third direction which is generally opposite to the first direction.

18. The method of claim 17 including the step of subsequently moving the selected cards in a fourth direction generally opposite to said second direction.

19. The method of claim 18 wherein said step of moving the selected cards in a third direction comprises tilting the cards by moving only one end in said third direction, and wherein the step of moving the cards in the fourth direction comprises engaging that part of the selected cards which were tilted up as the selected cards moved in the said third direction.

20. The method of claim 19 wherein said first direction is a downward direction.

21. A method for separating from a stack of cards arranged with an edge of all cards in alignment with each other, certain cards having a predetermined pattern of notches on said aligned edge, comprising the steps of presenting to the said edges of the cards in the stack, selector bars corresponding to the said pattern, exerting a force on the stack to move the same in a first direction toward the selector bars, whereby the cards having the said notch pattern move farther than the other cards as the nonnotched parts of the cards having the said pattern of notches moves between the said corresponding selector bars, moving the said other cards relative to the selected cards in a second direction which is generally perpendicular to said first direction, and moving the selected cards in a third direction generally opposite to the said first direction.

22. The method of claim 21 wherein said first direction is a downward direction and said second direction is horizontal and rearward and wherein said step of arranging the cards comprises arranging the cards on front and rear riser bars and said set of selector bars between said riser bars, and wherein said step of moving the selected cards downwardly comprises moving the riser bars below the selector bars corresponding to the said pattern.

23. The method of claim 22 wherein said step of raising the selected cards comprises tilting the forward ends of the selected cards by moving the front riser bar above the top of the rear riser bar.

24. The method of claim 23 wherein the step of moving the selected cards in the fourth direction includes engaging the parts of the selected cards which were tilted upwardly for moving the selected cards forwardly.

25. The method of claim 21 wherein the step of moving the selected cards in the first direction comprises moving the selected cards downwardly by frictionally engaging and ruffling the cards in the stack so that the selected cards fall downwardly as the raised selector bars enter the said notches while the rejected cards are held up by engagement of their nonnotched edge portions with the raised selector bars.

26. Apparatus for sorting from a stack of cards having at least one edge of all cards in alignment with each other, certain cards having a predetermined notch pattern on the said edge, comprising, means for positioning the stack of cards with the said edges in alignment with each other, means for presenting selector bars to said edge of the stack, the positions of which bars correspond to the predetermined notch pattern, and means for physically engaging the stack of cards to exert a force thereon urging the cards towards the said bars, the last said means including a rotating brush mounted to engage at least one of (a) the top or (b) the side edges of the cards to ruffle the cards to cause separation thereof, whereby the cards having the said notch pattern move farther than the remaining cards as the nonnotched parts of the cards having the said pattern of notches moves between the bars.

27. The apparatus of claim 26, wherein said means for physically engaging the cards comprises at least one rotating brush mounted to engage the top of the cards to ruffle the cards.

28. The apparatus of claim 27 wherein said rotating brush has at least one set of bristles comprising a plurality of axially elongated bristles staggered axially along and spaced angularly about the periphery of the brush.

29. The apparatus of claim 27 wherein said means comprises at least one further rotating brush mounted to engage a vertical edge of the stack of cards.

30. The apparatus of claim 29 wherein each of said brushes comprise at least one set of bristles comprising a plurality of elongated bristles staggered axially along and angularly spaced about the periphery of the brush.

31. Apparatus for sorting from a stack of cards certain cards having a predetermined pattern of notches on one edge thereof comprising front and rear vertically movable riser bars for supporting the stack of cards, and a plurality of selector bars between said riser bars, each movable to a raised vertical position such that any selected combination of selector bars can be raised, a camshaft, at least first, second and third cams mounted on said camshaft for rotational movement therewith, means for operatively connecting the first cam to the front riser to raise and lower the same, means for operatively connecting the second cam to the rear riser bar to raise and lower the same, and means for connecting the third cam to said selector bars for raising and lowering selected ones of said selector bars, whereby said front and rear riser bars and said selector bars are raised and lowered in predetermined sequence with each other upon rotation of said camshaft.

32. The apparatus as claimed in claim 31, including a lift bar extending beneath all the selector bars, a recess in each selector bar above the lift bar and positioned such that when the lift bar is raised it enters the recesses, and means for moving each selector bar laterally, to move the said recess laterally away from the lift bar whereby when said lift bar is raised, it engages the bottoms of the selected, laterally moved selector bars to raise the same, and wherein raising and lowering of the lift bars is dependent on the rotational position of said third cam.

33. The apparatus of claim 31 including a cover member above the cards and positioned to engage the upper portions of the cards of the stack not having the said notch pattern and moving those said cards horizontally away from the selected cards having the notched pattern, a fourth cam on the said camshaft, means operatively interconnecting this fourth cam to the cover member, whereby said cover member operates in predetermined sequence with said front and rear riser bars and said selector bars.

34. The apparatus of claim 33 including a vertical arm pivotable about an axis at its lower end, engaging said cover member at its upper end, and engaged by said fourth cam intermediate its upper and lower ends.

35. The apparatus of claim 31 wherein the means operatively connecting said first, second and third cams to said front riser bar, the second riser bar and the selector bars, respectively, comprise two-arm pivotable levers, one arm of which engages its respective cam, and the other arm of which engages its respective bar.

36. Apparatus for sorting certain selected cards from a stack of cards comprising: a means for supporting the stack of cards; means for vertically separating the selected cards from the remaining cards such that the upper edges of either the group of selected cards or the group of remaining cards are positioned above the upper edges of the cards of the other group; a housing, said housing including a horizontally movable cover member above the stack of cards and positioned to engage the uppermost one of said two groups of said cards; and means for interconnecting the means for vertically separating the cards and the cover member such that the cover member is operable following the vertical separation of the cards to move the said uppermost group of cards horizontally relative to the other group of cards.

37. The apparatus of claim 36 wherein said means for vertically separating the cards comprises means for lowering the selected cards, relative to the remaining cards, such that the upper edges of the remaining cards project above the upper edges of the selected cards, and said cover member includes a member projecting downwardly to engage the remaining cards and move them horizontally.

38. The apparatus of claim 37 including a means for moving the selected cards upwardly after the remaining cards have been moved horizontally.

39. The apparatus of claim 38 wherein said cover member includes means for reversing its direction of travel so that it subsequently engages the raised selected cards and moves them horizontally in a direction opposite to its first said horizontal movement, to further separate the selected cards from the remaining cards.

40. The apparatus of claim 39, wherein the means for interconnecting the cover member and the means for vertically separating the cards comprises a camshaft having a first cam thereon operatively connected to the cover member for determining the horizontal position thereof, and further cams fixed on the camshaft for determining the operation of the said means for vertically separating the cards.

41. The apparatus of claim 40, wherein said means for supporting the stack of cards comprises front and rear riser bars, the means for moving the selected cards upwardly comprises the said front riser bar, and the means for vertically separating the cards comprises a set of selector bars, and means for raising predetermined ones of said selector bars to cooperate with a predetermined pattern of notches on the lower edges of said selected cards, and wherein said front and rear riser bars and said selector bars are operatively connected to said further cams on the camshaft whereby the riser bars and the selector bars are operated in predetermined sequence with each other.

42. The apparatus of claim 41, wherein said means for operatively connecting said cover member and said first cam comprise a generally vertical drive arm pivotable about an axis at its lower end, said first cam being an eccentric mounted on the camshaft and engaged with an intermediate part of the drive arm for oscillating the same about said pivot axis as the camshaft rotates, the upper part of said drive arm engaging said cover member for moving the same horizontally as the drive arm oscillates.

43. The apparatus of claim 42 wherein said connection between the drive arm and the cover member includes a pin connection for permitting upward pivoting movement of the cover member about an axis through said pin.

44. The apparatus of claim 43 wherein said cover member includes a vertical sideplate, a cam follower on said sideplate, a stationary cam surface of said apparatus being located below said sideplate, said cam follower engaging said cam surface to determine the vertical position of the cover member relative to the cam surface, as the cover member moves first in one direction and then returns in an opposite direction.

45. The apparatus of claim 44, wherein said cam surface includes an upwardly projecting part for raising said cover member, said upwardly projecting part being spring loaded for resilient movement in the horizontal direction to delay the raising of the cover member as it returns in the said opposite direction.

46. The apparatus of claim 36, wherein the means for interconnecting the cover member and the means for vertically separating the cards comprises a camshaft having a first cam thereon operatively connected to the cover member for determining the horizontal position thereof, and further cams fixed on the camshaft for determining the operation of the said means for vertically separating the cards.

47. The apparatus of claim 46, wherein said means for operatively connecting said cover member and said first cam comprise a generally vertical drive arm pivotable about an axis at its lower end, said first cam being an eccentric mounted on the camshaft and engaged with an intermediate part of the drive arm for oscillating the same about said pivot axis as the camshaft rotates, the upper part of said drive arm engaging said cover member for moving the same horizontally as the drive arm oscillates.

48. In an apparatus for separating edge-notched cards having a predetermined pattern of notches, from other cards in a stack not having the predetermined pattern of notches, and including a set of selector bars, the set including one selector bar for each possible notch position on the cards, including means for moving certain ones of said selector bars corresponding to the said pattern of notches, relative to the other selector bars,

49. The apparatus of claim 48, wherein the means for mounting the cards adjacent the selector bars such that the separation of the said cards having a predetermined pattern of notches includes engagement of the cards with the selector bars, the improvement comprising, in combination a device for forming notches in the cards, said device including a holding means for holding a card to be notched, a notching means for forming notches in the cards; wherein said notching means is operatively related to said selector bars so that the notching means forms notches in the cards in response to engagement of the notching means with the said certain selector bars at positions corresponding to the positions of certain ones of said selector bars which have been moved to project outwardly, relative to the other bars to correspond to the said pattern of notches.

50. The apparatus of claim 49, said notching means comprise a punch and die unit for each notch position, a recess between corresponding punches and dies, the set of punch and die units being arranged side by side so that their recesses are aligned, said holding means being located adjacent said aligned recesses so that the edge of a card held by the holding means projects into said aligned recesses, and each punch being movable through its respective recess to notch the card when acted on by its respective selector bar.

51. The apparatus of claim 49, wherein the edge of each punch, adjacent its respective recess, is curved to facilitate movement of the punch through the recess and between dies of adjacent punching devices.

52. The apparatus of claim 48 wherein the notching means comprises a notching assembly including a punch, said assembly being mounted for movement along the edge of the card to be punched, and actuating means for actuating said punch to form a notch at positions corresponding to the said projected selector bars.

53. The apparatus of claim 52, wherein the actuating means includes a plunger means mounted on and movable with said assembly for engaging the projected selector bars, as the assembly travels along the card edge, to actuate the punch to form notches.

54. The apparatus of claim 53, including means mounted on and movable with said assembly for engaging each projected selector bar, after a notch has been formed, corresponding to the position of that bar, for moving that bar back to its normal position.

55. The apparatus of claim 53 wherein the actuating means further includes a bar extending over the punch for its entire length of travel along the edge of the card, a solenoid device,

lever means connecting the solenoid device to the bar such that when actuated the solenoid moves the bar downwardly to actuate the punch, regardless of the position of the punch in its travel along the card, and said solenoid being actuated in response to engagement of said plunger means with a projected selector bar.

56. The apparatus of claim 53 including a drive means for driving said assembly along the edge of the card, said assembly being connected to the drive means through a slipping connection so that when the plunger means engages a projected selector bar, the drive means continues while the assembly remains at that position to perform the punching operation.

57. The apparatus of claim 56 including means for disengaging the plunger means from the projected plunger after each punching operation, so that the assembly can continue to be moved along the edge of the card by the drive means.

58. The apparatus of claim 56 wherein said drive means includes a driving pulley, a cable between said pulley and said assembly, and a clamp connecting said cable to said assembly, the engagement of the cable on the driving pulley constituted said slipping connection such that the cable slips, relative to the pulley, when the plunger engages a projecting selector bar.
